UNITED STATES PATENT OFFICE.

EBER C. FLINT, OF SAGINAW, MICHIGAN.

FOLDING CHAIR.

SPECIFICATION forming part of Letters Patent No. 252,204, dated January 10, 1882.

Application filed September 16, 1881. (No model.)

To all whom it may concern:

Be it known that I, EBER C. FLINT, a citizen of the United States of America, residing at Saginaw, in the county of Saginaw and State of Michigan, have invented certain new and useful Improvements in Folding Chairs; and I do hereby declare the following to be a full, clear, and exact description of the invention, such as will enable others skilled in the art to 5
10 which it appertains to make and use the same, reference being had to the accompanying drawings, and to letters or figures of reference marked thereon, which form a part of this specification.

15 This invention has relation to improvements on Letters Patent for folding chairs granted to me on the 17th day of May, 1881, and numbered 241,533; and it consists in the novel construction and arrangement of the same, 20 whereby the chair may be arranged and locked for sitting purposes, as well as folded to occupy a small space in storing or when shipping, all of which will be hereinafter more fully explained.

25 The annexed drawings, to which reference is made, fully illustrate my invention.

Figure 1 represents a vertical sectional view of my improved chair. Fig. 2 represents a longitudinal sectional view of the same, taken 30 through line *yy*. Fig. 3 represents a side view of the chair folded. Figs. 4, 5, 6, and 7 represent detail views of parts of the same.

A designates the chair, which is composed of front and rear legs, *a a*, and back *a²*, pivoted at *a³*, where the legs cross each other. The seat *a'* is pivoted at *a⁴* to the upper and forward end of the legs *a a*, and between the same, while the opposite end is free and is provided with projections *b b* on each side to engage 35 and rest within grooves *b' b'* on the inner face of the sides of the back. Said seat is further provided on one side with a notch, *b²*, that engages a spring-fastening, *B*, that is secured at one end to the inner side of the chair, while 40 the other end of said spring is free and bent at right angles to form a point, *b³*, that enters a perforation in said chair, and on the oppo-

site side to the spring-fastening, and secured to the inner side of the chair, is a guide-pin, *b⁴*, placed beneath the bottom of the seat *a'*. 50

It will be observed from the above description that when the chair is open and ready for use the projections rest within the grooves *b' b'*, and the seat is supported at its rear thereby, and at the forward end by the pivotal connections to the upper end of the forward legs, *a a*, at the same time said seat is firmly but removably locked by means of the spring-fastening engaging the notch *b²* in the side of said seat, as shown in the drawings. 60

When it is desired to fold the chair the spring-fastening is pressed outwardly, which disengages the same from the notch *b²*, and the forward end of the seat is thrown rearwardly, thus removing the projections *b b* from 65 the grooves; and at the same time the seat rests on and is guided by the pin *b⁴* until the chair is folded, when the projections *b b* will rest in notches *b⁵ b⁶* made on the lower inner faces of the chair-legs *a a*, thereby permitting 70 the seat, when folded, to be within the framework or legs of the chair. The chair is braced and connected by the usual rounds, *b⁶ b⁶*, in the lower part thereof.

It will also be seen that a chair constructed 75 as described is simple in operation, durable, and cheap to manufacture.

Having thus fully described my invention, what I claim as new, and desire to secure by Letters Patent, is—

The folding chair herein described, consisting of the front and rear legs, *a a*, pivoted together at *a³*, and the seat *a'*, the seat having projections *b* and notch *b²*, and pivoted to the upper ends of the rear legs, the front legs being provided with notches *b'* and spring-fastening *B*, all combined and arranged as set forth. 85

In testimony whereof I affix my signature in presence of two witnesses.

EBER C. FLINT.
